DESIGN FOR A PILLOW

Paul E. L. Kolisch, San Francisco, Calif.

Application March 11, 1940, Serial No. 90,817

Term of patent 7 years

To all whom it may concern:

Be it known that I, Paul E. L. Kolisch, a citizen of Germany, residing at San Francisco, in the county of San Francisco and State of California, have invented a new, original, and ornamental Design for a Pillow, of which the following is a specification, reference being had to the accompanying drawing, forming a part thereof.

Fig. 1 is a perspective view of a pillow, showing my new design;

Fig. 2 is an end elevational view thereof.

The two opposite sides of the pillow not disclosed are similar to the two front sides illustrated. The pillow is provided on one end with a button and on its opposite end with a loop.

I claim:

The ornamental design for a pillow, substantially as shown and described.

PAUL E. L. KOLISCH.
